ILLUMINATED TAP

Lionel S. Hetherington, Baldwin, N. Y.

Application July 19, 1946, Serial No. 685,002

9 Claims. (Cl. 40—130)

1

This invention relates to illuminated taps and more particularly to an electrically illuminated tap adapted to be used as an advertising device.

One object of this invention is to advertise the beverage available on draught at the tap.

Another object is to visibly indicate the specific beverage to be drawn from a specific tap.

Another object is an illuminated tap-head which is detachably attachable to the control arm of a dispensing valve.

Other objects will appear from the detailed description which follows:

In accordance with this invention, the tap is provided with a hollow fenestrated head or handle fabricated out of a suitable translucent material which is detachably attachable to the tap control lever. The translucent head or handle forms a housing for an electric light bulb which is normally illuminated to clearly visibly display suitable advertising material through the display window to draw attention to the particular beverage on draught at the tap. The electrical circuit for the light bulb is controlled by the tap control lever; hence when the attendant operates the tap handle to draw the beverage the light bulb is extinguished.

In the drawings comprising two sheets of ten figures numbered Figs. 1 to 8, 8a and 9 inclusive.

Fig. 1 is a vertical cross sectional view of my improved tap handle and a suitable control system therefor, associated with a conventional tap.

Fig. 2 is a front view of a control switch and its associated strip wiring.

Fig. 3 is a horizontal cross sectional view of the control switch of Fig. 2.

Fig. 4 is an exploded view of my tap handle.

Fig. 5 is a vertical cross sectional view of a modified form of the invention.

Figs. 6 and 7 are detailed views of an insulated adapter.

Fig. 8 is a horizontal cross sectional view of a modified form of contact switch.

Fig. 8a is a longitudinal section taken along the line 8a—8a of Fig. 8, looking in the direction of the arrows.

Fig. 9 is a side view of another modified form.

Referring generally to Fig. 1, the tap or dispensing valve 22 is piped in the conventional way to a barrel or other container (not shown) containing the beverage which is on draught at the dispensing nozzle 20. The tap includes a suitable dispensing valve actuated by the control lever 21 which is pivotally connected to the dispensing valve 22. The tap 20 is supported in any suitable manner as by a counter, fountain, or

2

bar 23, and the control lever 21 is so biased by mechanism conventionally enclosed within the casing of dispensing valve 22, that when the tap is not in use the control lever 21 tends to resume an upright position. One suitable mechanism for so biasing the control lever 21 is shown and described in United States Letters Patent No. 2,034,420 granted to Peter M. Reiland et al. on March 17, 1936. When control lever 21 once attains its normal position, the spring washer 29 tends to retain the control lever 21 in such normal position. The tap 22 and its associated piping is grounded at 98.

The upper end of the control lever 21 is provided with a male threaded shank 24 from which the conventional form of a detachable handle ordinarily employed has been removed and replaced by the illuminated handle embodying the construction of this invention.

One form of illuminated handle embodying my said invention is shown in Fig. 1. As shown in Fig. 1, said handle includes a hollow head 31 made of any suitable translucent material, preferably a translucent molded plastic.

The handle 31 is provided with a window 32 fashioned out of a suitable translucent material such as Bakelite, Lucite, or the like, the window 32 being sealed at 34 into the hollow head 31, to prevent moisture from entering the hollow handle.

At the time the display window 32 is fabricated, suitable advertising matter 33 is embedded in the display window 32 so as to form an integral part of the window.

The advertising matter 33 may include the brand name of the beverage dispensed from the tap with which the handle 31 is associated, or it may contain other advertising matter if preferred.

The handle 31 may include a threaded shank 37 having one or more internal keyways 35 (Fig. 4), fashioned to receive the positioning ribs 36 of an insulated adapter 28. The adapter 28 may be fabricated from any preferred kind of insulating material but an adapter molded out of a suitable plastic material is relatively cheap and gives good results.

The adapter 28 which constitutes a detachable extension of the handle 31 provides a suitable holder for the lamp bulb 40. The adapter 28 may be detachably attached to the handle 31 in any preferred manner as by means of a threaded ring 30 so fitted as to abut against the annular shoulder 29 formed at the upper end of the adapter 28, so as to seat the handle 31 upon the

adapter 28 when the female threaded ring 39 is screwed over the threads of the male threaded shank 37. The positioning ribs 36 register with the keyways 35 formed in shank of the handle 31 to insure that the handle 31 will be so positioned relative to the valve control lever 21, as to correctly display the advertising matter 33 carried by the window 32.

The adapter 28 may be designed to receive any conventional type of electric lamp bulb 40, such for example as a lamp bulb having a conventional miniature screw base 41, in which case the adapter includes a lamp base holder 43 of the screw socket type and a central spring contact 39. The metal holder 43 is electrically connected by a suitable metallic strap to a contact pin 38 positioned in the outer wall of the adapter 28. The lower end of the adapter 28 is recessed said recess being female threaded to match with the male threaded stem 24 of the valve control lever 21. When a ground return signal circuit is employed, a female threaded metal bushing 27 is seated in the recess at the lower end of the adapter, to establish electrical continuity for the ground return of the signal circuit through the valve control lever 21 to the ground connection 98 (Fig. 1). Electrical continuity may be established between the central stud 42 of the lamp bulb 40 (Fig. 1) and the metal bushing 27 in any preferred manner, as by means of a central spring contact 39 which constitutes a resilient central electrode for the central stud 42 of the lamp bulb 40. The lamp holder 43 and the contact pin 38 and their associated metallic strap, and the metal bushing 27 and its associated spring contact 39 may all be secured in place during the molding of the adapter 28. When a lamp bulb 40 is screwed into the adapter 28, electrical continuity is established from the contact pin 38, through lamp socket 43, the filament of the lamp bulb, and lamp stud 42, through central spring contact 39 and metal bushing 27, valve control lever 21 to ground at 98, thus establishing a part of the lamp signal circuit.

By molding the shell of the hollow head 31 relatively thick and the display window 32 relatively thin, the intensity of the light emitted through hollow head 31 may be substantially reduced and the intensity of the light emitted through the display window 32 and its advertising matter 33 materially increased.

The valve control lever 21 of the dispensing valve 22 is biased in such a manner that when released it normally tends to assume a vertical position against the counter, fountain, or bar 23. A contact switch 50 which includes a plastic housing is mounted upon the counter 23 at the proper height to register with the contact pin 38 whenever control lever 21 returns to its normal upright position.

A rod 45 carrying a contact point 44 is slidably supported in the plastic housing of contact switch 50 in such a manner that the contact point 44 establishes electrical contact with the contact pin 38 whenever the valve control lever 21 returns to its normal position.

Referring to Figs. 2 and 3, the rod 45 may be made of any suitable insulating material such as molded plastic. The rod may be hollow to form a sleeve covering for the stem of the contact point 44. A continuity spring 48 establishes electrical continuity between the stem of contact point 44 and a contact plate 49 located within the plastic housing of contact switch 50.

The plastic rod 45 slides into the plastic hous-

ing of contact switch 50 against increased tension exerted by the continuity spring 48, thus providing a suitable follow between the contact point 44 and the contact pin 38 of the adapter 28 whenever valve control lever 21 approaches or moves off normal. This follow of contact point 44 insures electrical continuity between the contact pin 38 and the contact plate 49 of contact switch 50.

10 The plastic rod 45 is provided with an annular groove 46 adapted to receive a locking pin 47 (Figs. 1 and 2) which is slidably mounted in the plastic housing of contact switch 50. Thus when the barrel piped to the dispensing valve 22 is empty, the attendant may push the plastic rod 45 into the housing of the contact switch 50 until the pin 47 engages the annular groove 46 thus holding the contact point 44 out of electrical contact with contact pin 38 to break the signal circuit and extinguish the lamp bulb 40, as a visible indication that the barrel piped to the dispensing valve 22 is empty. After the empty barrel has been replaced with a full barrel piped to the dispensing valve 22, the locking pin 47 15 may be withdrawn from the annular groove 46, thus permitting the continuity spring 48 to push the plastic rod 45 outwards and re-establish the signal circuit for the lamp bulb 40 at contact pin 38, thus relighting the lamp 40 as a visible indication that the beverage is now on draught at the dispensing valve 22.

20 The plastic housing of contact switch 50 may be provided with a vent 51 (Fig. 1) to permit the escape of any moisture which may accumulate 25 inside the housing 50.

25 The contact plate 49 is located within the plastic housing of contact switch 50. It may be connected to a suitable source of low voltage in any preferred manner as for example, to the low voltage secondary winding 56 of an iron core 30 step-down transformer (Fig. 1), whose primary winding 55 may be connected in the conventional way to a suitable source of alternating current voltage 57. One side of the secondary winding 55 is electrically connected to the contact plate 49 over the low voltage supply lead 60, and the other side of the secondary winding 56 is connected through a fuse 58 to ground at 59. The ground side of the secondary winding 56 of the 35 transformer is fused at 58 so that any overload current will blow the fuse 58 and completely open the signal circuit through the low voltage secondary winding 56.

40 The signal circuit is preferably wired through a moisture-proofed prewired connector strip 54, consisting of one or more hollow conductors or tubular wires 53 embedded in the connector strip 54, preferably by molding the material while in a plastic condition. Where two or more tubular 45 wires 53 are molded in the connector strip 54, they are retained in parallel spaced relationship at a sufficient distance apart, so that the insulating material from which the connector strip 54 is molded enters in between the tubular wires 53 and completely insulates the tubular wires 50 from each other and protects them against external exposure.

45 The connector strips 54 (Fig. 2) are made in suitable lengths so that they can be laid in end to end abutment to construct a signal circuit of any desired length.

50 Electrical continuity is established between the adjoining sections of tubular wiring by inserting a double ended tapered pin 52—52 (Fig. 3) in 55 the adjoining ends of the tube wiring thus brid-

70

ing the conductors of the adjoining sections of tube wiring together. The diameter of each end of the double ended tapered pin 52—52 is such as to cause each tapered pin 52 to frictionally engage the inner wall of the tube wiring 53 and establish perfect electrical continuity.

One suitable form of double ended tapered pin is shown in association with the contact plate 49 of the plastic housing 50 (Fig. 3). The connector strips 54—54 (Fig. 3) are terminated in spaced relation so as to receive the plastic housing 50. The tapered pins 52—52 (Fig. 3) extend in opposite directions from the contact plate 49 into the oppositely disposed spaced connector strip sections 54—54 of the hollow tube wiring 53—53, so that each tapered pin 52 frictionally engages the inner wall of a section of tubing 53, thus establishing electrical continuity between the contact plate 49 and each section of tube wiring 53, while at the same time forming a bridge connection between the spaced tubular wires 53—53. Any desired number of sections of connector strip 54 may be electrically interconnected by means of the double ended tapered pins 52—52 associated with each contact plate 49 of each outlet unit 50.

Since the connector strips 54 are made of plastic material, they may be readily cut (as by sawing) into shorter lengths of any required size, to facilitate the installation of any desired wiring system having any required number of outlets for use in conjunction with any desired arrangement of dispensing valves 22—22.

A metallic signal circuit may be employed to replace the grounded signal circuit. When a metallic signal circuit is employed, the grounded connections 53 and 53 (Fig. 1) may be replaced by an insulated metallic conductor similar to the conductor 66 (Fig. 1). A metallic signalling system employs a connector strip or molding similar to the molding 54 but having two conductors embedded in the connector strip in parallel spaced relation instead of the single conductor 53 shown in Figs. 2 and 3 of the drawings. A connector strip containing twin tube wiring is shown generally in Figs. 8 and 8a, wherein the connector strip 66 contains two tubular conductors 67 and 68 which are bridged to the twin conductors of the adjoining section of connector strip by means of the tapered pins 67 and 68 (Fig. 8a). Where twin tubular wiring is employed, the plastic housing of the contact switch 71 contains a slidably mounted contact rod 72 carrying the separately insulated contact pins 73 and 74. Each contact pin 73 and 74 is retained in electrical continuity with its associated contact plate 100 or 102 by means of its continuity spring 99 or 101. Contact plate 100 is in electrical continuity with tapered pin 67, while contact plate 102 is in electrical continuity with tapered pin 68, so that the contact pins 73 and 74 may constitute a T connection or tap-off from the twin tubular wiring 69 and 70 of the signal system.

When a metallic circuit is employed for the signalling system, the insulated adapter 61 (Figs. 5, 6, and 7) is provided with twin insulated contact pins 63 and 64 adapted to register with the twin contact pins 73 and 74 of the contact switch 71. Insulated adapter 61 (Figs. 5, 6, and 7) is provided with one or more positioning ribs 62 which function in the same manner as the positioning ribs 35—36 of insulated adapter 28 (Fig. 4). The contact pins 63 and 64 of the adapter 61 are in electrical continuity with the screw 75

socket 81 and with the center spring contact 83 of the adapter. As best illustrated in Fig. 5, the center spring contact 83 is connected to the contact pin 64 by means of the metal strap 82, and the screw socket holder 81 is connected to the contact pin 63 by a metal strip 84. The lamp bulb 65 (Fig. 7) which may be of the miniature type is provided with a miniature screw base adapted to be screwed into the screw socket holder 81 so that the screw base of lamp bulb 65 is in electrical continuity with screw socket 81, and the central stud of lamp bulb 65 is in electrical continuity with center spring contact 83, thus establishing a completely insulated metallic circuit through the filament of the lamp bulb 65.

The hollow head 76 is provided with a window 77 suitably sealed in the head 76. Suitable advertising matter 78 is displayed in the window 77, the advertising matter 78 preferably forming an integral part of the window 77. The shank of the hollow head 76 may be undercut and male threaded at 79 to interengage the female threads of the threaded ring 80. The ring 80 is provided with an inwardly projecting flange which engages the annular shoulder 97 of the adapter 61 thus locking the hollow head 76 to the adapter 61, in the manner previously described.

The lower end of the adapter 61 is recessed, and to facilitate direct or indirect attachment to the valve control lever 21 the recessed lower end of the insulated adapter 61 may be female threaded as indicated at 85.

The conventional valve control levers 21 may be provided with male threaded shanks 24 of various sizes and threads, so that the insulated adapter 61 must be provided with suitable means for attaching the insulated adapter 61 to any valve control lever 21 regardless of the size or character of the thread of the male threaded shank 24. This may be accomplished by providing a reducer 25 having a male threaded end 26 adapted to threadably engage the female threaded socket 85 of the adapter 61, and a female socket 103 adapted to engage the male threaded shank 24 of valve control lever 21. A knurled locking washer 75 may be inserted upon the male threaded shank 24 to insure correct centering of the hollow head 76 upon the valve control lever 21 so as to face the window 77 in the proper direction to correctly display the advertising matter 78.

Fig. 9 shows the invention applied to the tap of a soda fountain. In this case the fountain 95 includes a dispensing valve tap 93 operated by a valve control lever 87. The hollow head 86 is provided with a window containing suitable advertising display matter 105, similar in scope to the display matter 33 and 78 of the hollow heads 31 and 76. A contact pin 89 is connected in a signal circuit which includes the filament of the lamp bulb 106 housed in the hollow head 86.

A suitable control switch 91 is attached to the arm of the fountain 95 by means of an adjustable pipe clamp 92 and its associated clamping screw 93. Low voltage supply lead 94 is connected to a suitable source of low voltage supply such as the low voltage secondary winding 56 of the transformer (Fig. 1).

The low voltage supply lead 94 is in electrical continuity with the contact point 90 of the control switch 91. The assembly of the control switch 91 is generally similar to the assembly of the control switch 50 (Fig. 3), so that when-

ever the valve control lever 87 is in an upright position, a signal circuit is completed through the filament of the lamp bulb 106 housed by the hollow head 86, through contact pin 89, contact point 90 and low voltage supply lead 94, to a suitable source of low voltage (such as the low voltage secondary winding 56 of Fig. 1), thus lighting the lamp bulb 106 to display the advertising material 105 through the window 104. When the handle 86 is operated, valve control lever 87 moves in such a direction as to separate contact pin 89 and contact point 90, thus interrupting the signalling circuit through the lamp bulb 106 and extinguishing the lamp and the display 105. Control lever 87 also opens the tap 88 to dispense the beverage into the drinking glass 96. When the valve control lever 87 resumes its normal (upright) position contact pin 89 re-engages contact point 90 to re-establish the signalling circuit, thus relighting the lamp 106 to again display the advertising matter 105 through the window 104.

While the miniature lamps 40, 65, and 106 have been described as of the screw base type, it should be understood that any other form of lamp may be used by modifying the adapters 28, and 61 to accommodate the desired type of lamp.

While there has been disclosed in this specification certain forms in which the invention may be embodied, it is to be understood that the said forms are shown for the purpose of illustration only, and that the invention is not to be limited to the forms disclosed, but may be modified and embodied in various other forms without departing from the spirit of the invention. In short the invention includes all of the modifications and embodiments coming within the scope of the appended claims.

What is claimed is:

1. In a normally illuminated dispensing tap and in combination, a dispensing valve, a control lever therefor, an electric lamp detachably mounted upon said control lever and insulated therefrom, a handle having a cavity formed therein, said cavity including a window, said handle being detachably mounted on said control lever and housing said electric lamp in said cavity, a pair of closure contacts, an electrical circuit including said lamp and said closure contacts, one of said closure contacts being carried by said control lever, said control lever when in normal position completing said lamp circuit through said closure contacts to light said lamp to normally illuminate said window, and said handle being operable when mounted to move said control lever off-normal to simultaneously open said valve to dispense a beverage and said lamp circuit at said closure contacts to extinguish said lamp and darken said window to visually indicate that the valve is in beverage dispensing position.

2. A tap-handle having a window and a cavity formed therein for containing advertising matter adapted when illuminated to be visible through said window, said handle having a hollow shank connecting with said cavity, an insulated adapter, a socket for mounting an electric lamp supported upon said adapter, said socket including electrodes spaced to engage the electrodes of an electric lamp, the upper portion of said adapter entering said shank to position an electric lamp when engaged between said socket electrodes within said windowed cavity to form a handle unit, one electrode of said lamp socket having a ground-forming connection, a closure

5 contact embedded in the exterior face of the wall of said handle unit and electrically connected to the other electrode of said lamp socket to extend the conductors of the electrical circuit over which said lamp is to be lighted to the exterior face of the wall of said handle unit, another contact separate from said handle unit, said handle unit being movable to extend said electrical circuit from said closure contact to said other contact, and said lamp when lighted illuminating said advertising matter.

3. A tap-handle having a window and a cavity formed therein for containing advertising matter adapted when illuminated to be visible through said window, said handle having a hollow shank connecting with said cavity, an insulated adapter, an electric lamp socket supported by said adapter, said lamp socket including electrodes spaced to establish electrical continuity with the electrodes of an electric lamp, the upper portion of said adapter entering said shank to position an electric lamp when engaged by said socket electrodes within said windowed cavity to form a mechanical unit, means for detachably mounting said mechanical unit upon the control-lever of a beverage dispensing valve, said means being electrically connected to one electrode of said lamp socket to ground one leg of the electrical circuit over which said lamp is to be lighted to the tap pipe line via said control-lever, a closure contact embedded in the exterior face of the wall of said mechanical unit and electrically connected to the other electrode of said lamp socket to further extend the electrical circuit over which said lamp is to be lighted to the exterior face of the wall of said mechanical unit, to combine said mechanical unit, said lamp socket electrodes, and said electrical connections therefor, into one assembly unit, said electrical circuit including a second contact engaged by said closure contact when said lamp is to be lighted, and said lamp when lighted illuminating said advertising matter.

4. In a tap-handle and in combination, an insulated holder threaded for mounting upon the actuating lever of a beverage dispensing tap, the upper end of said holder defining an annular shoulder, an electric lamp socket mounted upon the upper end of said holder, an electric lamp mounted in said lamp socket, an electrode extending laterally through the side wall of said holder and electrically connected with one electrode of said lamp socket, a second electrode extending axially through said holder to electrically interconnect the other electrode of said lamp socket and the grounded actuating lever of said tap, a handle having a hollow fenestrated head terminating in a male threaded throated shank, the window containing advertising matter and light transmitting material, the upper end of said holder being keyed for engagement against rotation within said throated shank when said annular shoulder and said male threaded shank are in axial alignment thus positioning said lamp in proper position to illuminate and thus display said advertising material through said window whenever the electrical circuit for lighting said lamp is closed, a female threaded coupling for drawing said male threaded throated shank 60 against said shoulder to lock said handle to said holder, and a contact point for engaging said laterally extending electrode in completing said electrical circuit.

5. In a lever-controlled grounded tap-valve and in combination, an electric lamp, a socket

for said electric lamp, said socket including spaced electrodes and a base member, said base member having an annular side wall and being detachably mountable upon the movable arm of the tap-grounded control-lever, one socket-electrode being connected to, and the other socket-electrode being insulated from, said control-lever, a handle, a shank merging with and in continuation of said handle, said handle and shank being hollowed out to form a throated cavity, said cavity including a window, said lamp socket nesting within said throated cavity, a third electrode electrically connected to said insulated electrode and electrically insulated from said grounded electrode to complete so much of the electrical circuit for lighting said electric lamp when secured in said socket as is movably carried by said control-lever, said third electrode extending radially through the annular side wall of said base member to provide a surface contact, a contact stationary relative to said surface contact, and said surface contact moving in unison with said control-lever to close and open said electrical circuit through said stationary contact to light and extinguish said lamp.

6. In a lever-controlled tap-valve and in combination, an electric lamp, a socket for holding said electric lamp, said socket including spaced electrodes and a base, said base having an annular side wall and being detachably mountable upon the movable arm of the control-lever, said spaced electrodes being insulated from the control-lever and from each other, a handle, a shank merging with and in continuation of said handle, said handle and shank being hollowed out to form a throated cavity, said cavity including a window, said lamp socket nesting within said throated cavity, twin electrodes extending through the annular side wall of said base in spaced relation to provide a spaced pair of surface contacts, said paired electrodes being substantially flush with said annular side wall and being separately electrically connected to the electrodes of said lamp socket to establish in part a metallic circuit for said electric lamp secured in said socket to light said lamp and illuminate said window, a pair of spaced circuit contacts, a source of voltage connected therebetween to complete the metallic circuit for said lamp, and said spaced surface contacts moving in unison with said control-lever to cause said metallic circuit to close and open at said spaced contacts to light and to extinguish said lamp.

7. In a handle for a lever-controlled tap-valve and in combination, a handle having a cavity formed therein, said cavity including a window, an insulated holder comprising an electric lamp socket, said holder having an annular base and being slidably insertable in said cavity, said holder constituting means for detachably mounting said handle upon the control-lever of the tap-valve for movement in unison with said control-lever to open and close the tap-valve, one electrode of said lamp socket being insulated from said control-lever, a second electrode protruding through the curved wall of the annular base and electrically connected to said insulated electrode, said holder being keyed to said cavity to correctly position said window relative to said second electrode, a stationary contact, said second electrode constituting a part of an electrical circuit, completed through said stationary contact when said control-lever is moved into position to close said

tap-valve, for lighting an electric lamp secured in said socket, to illuminate said window.

8. In a tap-handle and in combination, a handle having a cavity formed therein, said cavity including a window, advertising matter positioned in said cavity, said matter when illuminated being visually displayed through said window, an electric light socket having an annular base, said light socket slidably nesting in said cavity, an electrode electrically connected with one electrode of the light socket and protruding radially outwards through the annular side wall of said annular base to define an exposed terminal contact having its contact face substantially flush with the face of said annular side wall, and means for insuring correct registry between said handle and said light socket when nested in said cavity to correctly position said window relative to said terminal contact.
9. In a lever-controlled electrical circuit for visually advertising a beverage dispensed by a tap-valve and in combination a tap-valve control-lever, a socket for an electric lamp, an electric lamp positioned in said socket, said socket including spaced electrodes, said socket being detachably mountable upon the movable arm of said control-lever for actuating the tap-valve to dispense the beverage, a handle, said handle being hollowed out to form a windowed cavity for containing advertising matter peculiarly indicative of the specific beverage dispensed from said tap-valve, said advertising matter when illuminated being visible through said window, said lamp socket being detachably mounted in said cavity,
- 30 an electrical circuit for applying operating current to said electric lamp when bridged between the spaced electrodes to light said lamp and thus illuminate said advertising matter, said circuit including a movable branch carried by said control-lever and a relatively fixed branch complementary to said movable branch, said movable branch including said spaced electrodes, said bridging lamp and two other electrodes separately electrically connected at one end to said spaced electrodes
- 40 and extending at their opposite ends through the side wall of said socket to provide a pair of spaced contact points, said complementary branch including a pair of spaced contact points whose spacing corresponds to the spacing between the
- 50 spaced contact points of said movable branch, and the spaced contact points of said movable branch being carried by said control-lever into electrical contact with the spaced contact points of said complementary branch when said dispensing valve is closed, to light said lamp and illuminate said beverage-indicative-advertising-matter.
